UNITED STATES PATENT OFFICE

2,605,719

LADING TIE FASTENER

Edward Payson Smith, Winnetka, and Malcolm S. Johnson, Chicago, Ill., assignors to Illinois Railway Equipment Company, Chicago, Ill., a corporation of Illinois

Application February 28, 1951, Serial No. 213,158

3 Claims. (Cl. 105—369)

1

Our invention relates to means, which are intended to be fixedly secured to the car walls of a house car, for anchoring or securing the lading holding straps or tie elements and permit easy application and/or removal of the tie straps without damage to the car wall or structure and without causing damage to lading which may subsequently be loaded into the car.

Our invention relates to means intended to be fixedly applied to the interior wood lining of railroad box or house cars in such a manner as to provide smooth interior walls without protruding surfaces which would interfere with subsequently loaded lading; namely, an anchor or tie strap fastener which eliminates all possibility of injury to lading loaded in the car.

The invention has for its object, the provision of an anchor or fastening means which may be readily applied to the inner lining or walls of existing cars and lie flush therewith without change in car construction and adapted to receive the conventional steel tie straps at present in use, whereby undesirable shifting or movement of the lading may be prevented and/or temporary partitions or bulkheads for mixed car loads may be secured in place.

An object of our invention is the provision of a comparatively inexpensive and simple unitary structure which may readily be applied to the car lining and extend flush therewith, at preselected places, without marring the car interior lining and without destroying the sealing nature of the lining against shifting of any bulk or granular commodity in the car and against the introduction of moisture due to exposure to the car exterior of temperature conducting metal portions.

The foregoing objects and advantages, as well as advantages inherent in the invention, will all be readily comprehended from the following detailed description of the accompanying drawings wherein—

Figure 1 is a perspective view of a portion of a railroad car side wall construction with our improved anchor or tie strap holder shown applied and with an end of a tie strap applied thereto.

Figure 2 is a similar view with the tie strap omitted and the upper part of the anchor broken away.

Figure 3 is a perspective view of the rear side of the anchor member.

Figure 4 is a sectional perspective of the rear side of the anchor taken on the line 4—4 of Figure 3, with a portion of the backing or guide strip broken away.

Our improved tie fastener or anchor lends itself to the use of any suitable type of wire or other more or less flexible tie means, but is especially adapted to the use of the conventional type of flat steel strapping of flexible and bendable character and in the specific exemplification consists of an annular disc-like body member 10 which is intended to be rigidly secured to the car wall or inner lining 11. The car inner wall of

house cars generally consists of tongue-and-groove boards of preselected thickness extending lengthwise of the car and secured to the usual wall framing or vertical side posts, indicated at 12, and applied prearranged distances apart.

In order to enable easy application of our improved anchor or fastener, it is preferably of annular or disc-like form thus enabling the use of a suitable auger or drill for providing an annular socket in the wood sheathing or inner lining boards 11 for reception of the fastening member.

The disc-like member 10 preferably consists of a metal casting of preselected diameter with a rearwardly disposed rim 13 of predetermined depth and provided with a pair of spaced apart transversely disposed ribs 14, 14 arranged parallel with each other. These ribs are flush with the outer perimeter of the rim 13 and at their ends, adjacent the rim, are united by the shelf-like web portions 15, 15, see Figure 2.

The casting intermediate the parallel ribs 14, 14 has a transversely extending opening or slot, as shown at 16, which extends entirely through the casting to the forward side of the anchor where it is bisected by the integral bar or bridge 17 which spans the cavity in the forward face of the anchor and constitutes the member or anchoring bar to which the tie means or straps are secured. The edges 18 of this anchor bar preferably are somewhat convex, see Figure 1, and the edges made arcuate or rounded as shown more clearly in Figure 2 at 19 to eliminate the possibility of tearing the lading tie straps and to distribute the pulling strains when the strap extends at an angle.

In order to close the rear side of the open slot 16 in the member 10 and to facilitate threading the tie strap beneath the bridge or bar 17, and provide a smooth surface, we provide the smooth surfaced backing or concaved closure plate 20 which extends throughout the length of the slot or opening. The ends of the closure strip or plate 20 preferably are shown slightly narrower to facilitate manipulation and to fit the sockets 15a at the ledges or shelf-like web portions 15, 15 and the length of the backing plate is somewhat greater than the distance between the diametrically opposite shelf-like portions 15, 15 to permit the ends of the backing plate 20 to be bent back upon the plate with the distal ends then bent outwardly to fit beneath or back of the portions 15, 15, as shown at 21, 21 in Figure 2, thereby clamping the backing plate 20 in position and maintaining the plate 20 in the rearwardly bowed condition, as shown in Figure 2, and in spaced relation with the tie strap fastening bar 17. Our improved anchor is intended to be imbedded in the car lining which, by means of a suitable drill, is provided with an annular bore or socket, thus leaving a more or less roughened sheathing surface at the rear of the opening and the passage through the anchor which

would interfere with the easy threading of the tie straps. As the conventional tie elements generally consist of flat metal straps whose sharp ends are apt, during insertion, to dig into the wood sheathing or lining, we provide a smooth surfaced backing member of more or less resilient sheet metal which places the main body of the anchor under sufficient pressure against the heads of the screws or bolts 22, thereby holding the anchor against vibration. The backing member at the rear of the opening in the anchor causes the tie strap or element to be guided in its passage through the socket and about the integral tie bar 17. With the backing strip or member fitting more or less snugly between the anchor ribs 14, and in interengaging holding engagement with the ledges 15, any subsequent granular lading will be prevented from sifting between the car lining.

The backing plate 20 is of width substantially equal to the distance between the ribs 14, 14 at the rear of body member 10, while the bow of the plate 20 is such as to approximate the depth of the ribs 14, 14 and of the perimetrical flange or rim 13, so that when the anchor disc is secured in place the backing plate, by reason of its contact with the undrilled portion of the lining 11, will be flexed and induce the bent ends thereof to effect firmer binding relation with the shelves 15, 15 against vibration and chatter.

As previously stated, the car lining boards 11 coincide with the car wood posts 12 and at preselected elevations are bored to a depth less than the thickness of the car lining boards and approximately to the thickness of the anchor 10 so the latter will lie flush with the face of the lining as shown in Figures 1 and 2.

The anchor 10 is provided with a plurality of screw or bolt receiving holes for flat-headed screws or countersunk bolts as shown at 22. The screws or bolts extend through the undrilled portion 23 of the car lining boards and take into the wood side post 12 as shown in Figure 2.

When the screws or bolts 22 are fully screwed into place, the camber in the backing plate 20 will be against the undrilled portion 23 of the lining board and thereby exert outward pressure on the rear side of the anchor and ensure stability or firmness of the anchor.

Our improved anchor preferably consists of a casting except for the backing strip 20 in order to facilitate production and also provide a smooth guiding surface for the introduction of the tie strap.

As previously stated, the bridge or tie strap attaching bar 17 preferably is provided with convex side edges so as to apply the load or pulling strain at the center of the bridge and prevent possible tearing at the edges of the tie band or strap; and also to accommodate any slight angularity the band might take.

We have described what we believe to be a simple embodiment of the invention, but certain modifications may be possible without, however, departing from the spirit of our invention as defined by the appended claims.

What we claim is:

1. A lading tie fastener for a railroad house car comprising a main body or anchor member adapted to be embedded in and flush with the car lining provided with a transversely disposed elongated opening therethrough and provided with a perimetric rearwardly disposed flange, transversely disposed ribs on the rear face located at opposite sides of and adjacent said opening and

ledge forming portions integral with the ends of said ribs and at the ends of said opening; and a backing or slide plate coextensive with said opening and having rearwardly bent hook-like ends arranged to form holding interengagement with said ledge forming portions, said plate being coextensive with said opening and arranged between said ribs to confine said opening therebetween; a transversely disposed tie strap holding bar integral and flush with the front face of the body member bridging said opening and spaced from said backing plate to provide tie strap receiving space therebeneath; and means involving a pair of bolt and screw receiving apertures through the flange portion above and below said opening whereby the anchor member may be secured in place.

2. A lading tie fastener adapted to be secured to the lining boards of a railroad house car comprising a body member adapted to be embedded in the car lining and having a rearwardly disposed perimetrical flange with bolt or screw-receiving apertured portions and provided with a transversely disposed opening therethrough, transversely arranged parallel ribs defining the longitudinal margins at opposite sides of said opening, the ribs at the ends of the opening being united by ledge-forming webs; a concaved backing plate arranged in said opening with its ends curving outwardly and bent backward into hook-like portions arranged in interengaging relation with the rear sides of said ledge-forming webs; and an integral tie strap holding bar portion bridging said opening and flush with the forward face of the body member and spaced from said backing plate to permit passage of the tie strap therebeneath.

3. A lading tie fastener adapted to be secured to the lining boards of a railroad house car comprising a disc-like body member of prescribed thickness provided with a transverse opening therethrough, the rear side of the member being provided with transversely extending ribs circumscribing the opening and providing rearwardly sloping ledges at the ends of the opening; a concaved smooth-faced backing strip arranged in said opening with its ends sloping outwardly and bent rearwardly into hook-like portions adapted to effect interengaging holding relation with said ledges; a tie strap attaching bar integral with said body member and bridging said opening at the forward face of said member and spaced from said backing strip to permit passage of a tie strap; the body member at the rear having a perimetrical rearwardly extending flange being integral with said ledges, the flange and said ribs and all lying in the same vertical plane to permit snug contact with the car lining boards and thereby provide a seal against filtration to the rear of the body member.
